(57) **CLAIM**

The ornamental design for a rail for use in a server equipment rack, as shown and described.

DESCRIPTION

FIG. 1 is a front top perspective view showing our new design;

FIG. 2 is a rear bottom perspective view thereof;

FIG. 3 is a front elevation view thereof;

FIG. 4 is a rear elevation view thereof;

FIG. 5 is a top plan view thereof;

FIG. 6 is bottom plan view thereof;

FIG. 7 is a right side view thereof;

FIG. 8 is a left side view thereof;

FIG. 9 is a front bottom perspective view thereof;

FIG. 10 is a perspective cross sectional view taken from section view 10-10 of FIG. 9;

FIG. 11 is a perspective cross sectional view taken from section view 11-11 of FIG. 9;

FIG. 12 is a front top perspective view showing an alternative embodiment of our new design;

FIG. 13 is a rear bottom perspective view of FIG. 12;

FIG. 14 is a front elevation view of FIG. 12;

FIG. 15 is a rear elevation view of FIG. 12;

FIG. 16 is a top plan view of FIG. 12;

FIG. 17 is bottom plan view of FIG. 12;

FIG. 18 is a right side view of FIGS. 12; and,

FIG. 19 is a left side view of FIG. 12.

The broken lines shown in FIGS. 12-15 are included to show unclaimed subject matter only and form no part of the claimed design.
